CLAIM

The ornamental design for a vegetable-themed time device clock face, as shown and described.

DESCRIPTION

FIG. 1 is a front elevation view of a vegetable-themed time device clock face, showing the new design in a first environment of use;

FIG. 2 is a front elevation view of the vegetable-themed time device clock face, showing the new design in a second environment of use, as applied to a wrist-watch; and,
FIG. 3 is a front elevation view of the vegetable-themed time device clock face, showing the new design in a third environment of use, as applied to a clock.

The broken lines in the drawings illustrate environment and form no part of the claimed design.
